HANDBAG CONSTRUCTION

Leslie L. Stucker, Bronx, N. Y., assignor to Lou Goldsmith Handbag Corp., New York, N. Y., a corporation of New York

Application July 5, 1952, Serial No. 297,271

2 Claims. (Cl. 150—28)

1

This invention relates to a handbag construction.

It is an object of my invention to provide a handbag or pouch for ladies characterized by the features of the employment of sheeted fabric, such as leather which may, without the use of any metal or like framework, be distended to present an ornamental appearance and, when not filled, may occupy the minimum amount of space, to serve as an accessory for the storage of flat objects.

It is contemplated by my invention to provide a handbag or pouch wherein two congruent segments are joined to each other, said segments having a filling aperture and a closure therefor which do not add bulk, whereby the handbag may, in one condition, serve for the storage of flat objects and occupy a minimum amount of space but may be readily converted into a pouch of highly desirable appearance without the employment of rigid metal or like frames, and characterized by the provision of congruent layers of leather or the like, one of which serves as the bottom, the other of which is the top, the latter having a filling opening and drawstring guides to close the opening, which may flexibly be disposed within the filling aperture when not used as a pouch, in no way to pucker or add bulk to the layers, and further characterized by joining of the layers to each other, to provide predetermined lines of fold, thereby giving the handbag a highly ornamental appearance.

To attain these objects and such further objects as may appear herein or be hereinafter pointed out, I make reference to the accompanying drawings, forming a part hereof, in which—

Figure 1 is a top plan view;

Figure 2 shows my device extended to form a pouch;

Figure 3 is a bottom view of the handbag shown in Figure 1;

Figure 4 is a fragmentary section taken on the line 4—4 of Figure 1;

Figure 5 is a magnified section taken on the line 5—5 of Figure 1.

Making reference to the drawing, I show a handbag comprising an upper segment 10 and a lower segment 11, which are cut to the same outline and arranged congruently to lie substantially in a flat plane. The peripheral edges of the sections 10 and 11 are joined to each other by the seam 12.

In the illustration shown, the sections 10 and 11 are substantially of square outline and, in addition to the seam 12, have alternate sections

5 stiffened medially by turning the corners 13 and stapling or otherwise fastening the turned segment to the upper facing sheeting 10. By way of illustration I employ the rivets 14 to hold the turned corners 13, thereby providing alternate sections having a stiffened edge 15 between the peripheral seam 12, for purposes which will appear as this description proceeds.

The bottom segment 11 is provided with a bottom contouring stiffener 16 comprising layers of sheeting 17 and 18, sandwiching weighted disks 19 and 20 therebetween and held in position by the row of stitches 21.

15 The upper layer 10 is formed with a mouth 22 by cutting the sheeting 10 and forming a fold or beaded edge 23. A flap 24 has a turned-in fold 25 sandwiching therebetween a series of loops 26, yieldable independently of the fabric of the upper layer 10, and held thereto by rows of stitches 27. Through the loops 26 there are threaded in groups, arranged in opposed effective relation, the drawstrings or ropes 28 and 29 which have oppositely directed convolutions 30 and 31, respectively, through each group. The drawstrings or ropes 28 and 29 may be bound at their ends by the coupling buttons 32 and 33, respectively.

20 It will be understood that in a measure, though not as desirable, a hem may be employed at the mouth 22 instead of the loops 26, for guiding the drawstrings. It is to be observed that the hem will not lie as flat when the handbag is not used as a pouch and cause a less desirable appearance.

25 It will be observed that by this construction the handbag may normally lie flat by reason of the congruent position of the upper and lower layers 10 and 11. The flexibility of the loops 26 in no way puckers the layers. In this position, toilet articles, handkerchiefs or the like may be stored by insertion through the mouth 22 between the convolutions 30 and 31. When one grasps the drawstrings or ropes 28 and 29, and while holding the same snaps the handbag, a novel, ornamental shape is assumed by the handbag, as shown in Figure 2, occasioned by, first, the contour given by the disks 19, 20 in the bottom and, second, the alternate arrangement of the stiffening elements formed by the corner flaps 13 with relation to the seams 12.

30 Thus, as the drawstrings exert a closing effect on the loops 26, the handbag is shaped into a series of fluted extensions 34 and depressions 35, radiating from the bottom to the mouth, which flutes or depressions are substantially symmetri-

ecally extended from the bottom to the suspending drawstrings.

It will be understood that while I have shown and have described the congruent layers 10 and 11 as being of relatively square outline, various other symmetrical polygonal figures or arcuate figures may be employed.

It will also be understood that while the layers 10 and 11 may be of any material, such as leather, buckskin, and are illustrated in unlined condition, I may employ a lining and that likewise various fabrics or other sheeted materials may be employed, without departing from the spirit of my invention.

It will further be observed that while I have shown and have described the flap 24 serving in the nature of a reinforcement for the mouth of the pouch, that this member may be extended for a more substantial length and when the pouch is tilted, will serve to prevent accidental spilling of the contents, as the contents will thus be deflected.

In general, I have devised a novel handbag which may be economically produced and which is capable of being stored in a flat condition, thereby taking up the minimum amount of space and which is convertible by a simple flicking operation to a highly ornamental and capacious pouch. It will also be observed that by the construction used, not only is there a highly desirable storage receptacle furnished but the use of the construction described assures the maintenance of a flat and uncreased condition of the pouch with the minimum amount of attention.

Having thus described my invention and illustrated its use, what I claim as new and desire to secure by Letters Patent, is:

1. A handbag comprising upper and lower co-extensive layers joined to each other at the perimeter, the lower of said layers having a central stiffening member, the upper of said layers having a central mouth portion including flexible loops through which drawstrings are threaded, the peripheral edges of the layers having spaced stiffening elements whereby the drawstrings draw the assembly into a pouch along predetermined folds.

2. A handbag comprising a pair of congruent, flat, polygonal sheets joined at their peripheral edges and arranged in an upper and lower layer, the lower layer forming a bottom and including a central stiffener, the upper layer having a cut-out forming a filling mouth adjacent the center and drawstrings for closing said mouth, the periphery of said layers having spaced stiffeners adjacent thereto whereby the drawstrings shape the layers along alternate radial flutes and folds when suspended therefrom.
